H. P. CHANDLER

CONDUCTOR SUPPORT

Filed May 13, 1925

UNITED STATES PATENT OFFICE.

HOMER P. CHANDLER, OF MANSFIELD, OHIO, ASSIGNOR TO THE OHIO BRASS COMPANY, OF MANSFIELD, OHIO, A CORPORATION OF NEW JERSEY.

CONDUCTOR SUPPORT.

Application filed May 13, 1925. Serial No. 29,933.

My invention relates to a support for conductors and has particular reference to a support for a trolley wire conductor and a feeder conductor in which the feeder conductor will supply current to the trolley conductor. The device, however, is adapted to support other conductors than trolley conductors if so desired.

The object of my invention is to provide a device which may be secured to an overhead support and which is arranged to be engaged with and disengaged from a conductor and provide means to support a second conductor which shall act as a feeder or supply conductor for current to the trolley conductor and which will also act as a conductor between the feeder conductor and the trolley conductor.

It is quite the practice, especially in mine haulage work, to support the trolley wire conductor directly to an overhead hanger or other support secured to the roof of the mine, and to support a feeder conductor for the trolley conductor upon brackets secured to the side wall of the mine or to the roof of the mine by means of hangers other than those for securing the trolley conductor to the roof. In such practice, connections are made at intervals between the trolley conductor and the feeder conductor, but it will be quite apparent that two separate supporting mechanisms for the conductors means considerable extra expense in installing the system and may amount to as much as twice the cost of installing the trolley wire alone. Therefore, I have devised means of combining the two separate supporting systems into one whereby the cost of installation is greatly reduced through the reduction of labor and material, and a much more efficient system is secured through short connections between the feeder conductor and the trolley conductor.

My invention resides in the new and novel construction, combination and relation of the various parts hereinafter fully described and disclosed in the accompanying drawing.

In the drawing:

Fig. 1 is a side view of my invention.

Fig. 2 is an end view of Fig. 1.

Fig. 3 is a transverse sectional view on the center line of Fig. 1.

In the preferred form of my construction I employ a member 1 provided with a

threaded boss 2 by means of which the device is secured to an overhead hanger or support.

I also provide a pair of clamping jaws 3 provided with means 4 to engage the conductor to be supported and the device as shown is arranged to support a trolley wire conductor by the members 4 entering the grooves along the side of the trolley conductor. The jaws 3 are pivotally secured together by means of the transverse pintle 5 and the jaws are secured to the pintle 5 by means of the lugs 6 which are alternately spaced upon the pintle 5. Also secured to the pintle 5 is a boss 7 threaded upon the outside to receive a threaded nut 8 which moves up or down upon the threaded surface of the boss 7, depending upon the direction of rotation of the nut 8. The nut 8 is provided with an annular flange 9 which engages the grooves 10 in the jaws 3 and it will be evident that as the nut 8 moves up or down upon the boss 7 that the jaws 3 will be moved into or out of engagement with the trolley conductor 11. The member 1 is provided with a groove 12 adapted to receive a feeder conductor 13 and the member 1 is also provided with a ductile tongue 14 arranged to be formed or bent into engagement with the conductor 13 as shown by the dotted construction in Fig. 3.

The boss 7 is provided with a threaded recess 15 and the member 1 is provided with a threaded boss 16 by means of which the boss 7 is secured to the member 1. It will be quite evident, however, that the bosses 7 and 16 may be formed as a single unit. In other words, the boss 16 would be enlarged to the diameter of the boss 7 and will be provided at the lower end with the projecting member 17 secured to the pintle 5 for supporting the jaws 3. The lugs 6 are arranged on either side of the members 17 for securing the parts in pivotal relation with respect to the pintle 5.

The member 8 is also provided with a lug 18 which is originally formed upright and after the parts are assembled the lug 18 has its upper edge rolled inwardly so that it will engage with the flange 19 and prevent the nut 8 from rising upon the boss 7 as far as it would prior to the flange 18 being rolled inwardly. By the use of the flange 18 it is possible to position the pintle

5 in place by moving the member 8 to its extreme height, then placing the pintle 5 in position, together with the jaws 3, then lowering the member 8 and rolling the 5 flange 18 inwardly and this will prevent the member 8 from rising upon the boss 7 a sufficient distance to permit the release of the pintle 5.

10 The boss 16 connected to the member 1 and also to the boss 7 acts as a conductor or current equalizer between the conductors 11 and 13.

15 It will be noted that the axis of the boss 2 cuts the axes at right angles of the conductors 11 and 13, and that the axes of these three members rest in a common plane.

20 Also, the axes of the members 11 and 13 are parallel and spaced, but at right angles to the axes of the member 2. Such a construction brings the weight in a central line with respect to the hanger to which the device is supported, therefore, so far as the weight of the conductors is concerned, 25 places no side or bending strains upon the parts of the device and such bending strains as do occur in the use of the device are due to the conductors taking a curve.

30 It will be evident to those skilled in the art that I have devised a single mechanism which will support the two conductors from a common hanger, and that there are modifications which may be made from that construction which I have shown and which 35 will fall within the scope of my invention, therefore, I do not wish to be limited other than by my claims.

I claim:

40 1. A conductor support comprising a primary support and a secondary support, the primary support comprising a supporting boss provided with means to secure the support to a hanger, an open groove to receive a feeder conductor, means to be formed 45 about the feeder conductor to engage and secure the conductor in place, the secondary support comprising a pair of jaws to engage the conductor to be supported, means to move the jaws either into or out of engagement with the conductor and means to 50 secure the jaws to the primary support and

to conduct current from the feeder conductor to the conductor to be supported.

2. A conductor support for two conductors comprising a primary support for 55 one conductor, a secondary support for the other conductor, means electrically connecting the supports together, the secondary support comprising pivotal means secured to the connecting means to engage 60 and grip a conductor to be supported, means mounted on the connecting means to move the pivotal means into engagement with the conductor to be supported, and means to connect the support to a hanger. 65

70 3. A conductor support comprising a member provided with means to secure the support to a hanger, a pair of jaws to engage and grip a conductor to be supported, means to support a feeder conductor to supply current to the conductor to be supported, bendable means to grip the feeder conductor and means to move the jaws into engagement with the conductor to be supported. 75

75 4. A conductor support comprising a member provided with means to secure the support to a hanger, a pair of jaws to grip a conductor to be supported, hook shaped means to support a feeder conductor in conductive relation to the jaws and means to move the jaws into gripping engagement with the conductor to be supported, the axes of the first means, the feeder conductor and the conductor to be supported positioned in a common plane. 80

5. A conductor support comprising a member provided with a securing means to attach the support to a hanger, a pair of jaws to be moved into engagement with a 90 conductor to be supported, means to receive a feeder conductor, means to be bent around the feeder conductor to hold the conductor in position, and means to move the jaws into engagement with the conductor, the 95 axes of the conductors being spaced and parallel and at right angles to the axis of the securing means.

In testimony whereof I affix my signature..

HOMER P. CHANDLER.
